CLAIM

The ornamental design for a chair, as shown and described.

DESCRIPTION

FIG. 1 is a perspective view of a chair showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

A bottom view thereof is omitted since it does not contain ornamental features. The heavy broken line showing of stitch lines in FIGS. 1-6 forms portions of the claimed design, while the light broken line showing of portions of the chair in FIGS. 1-6 forms no part of the claimed design.
